UNITED STATES PATENT OFFICE.

WILBUR B. GRANT, OF ELMHURST, NEW YORK.

HOSPITAL MEDICINE-TRAY.

1,306,591.

Specification of Letters Patent. Patented June 10, 1919.

Application filed October 7, 1918. Serial No. 257,200.

To all whom it may concern:

Be it known that I, WILBUR B. GRANT, a citizen of the United States, and a resident of Elmhurst, borough of Queens, in the county of Queens and State of New York, have invented a new and Improved Hospital Medicine-Tray, of which the following is a full, clear, and exact description.

This invention relates to trays or carriers, and has particular reference to carriers or holders for a plurality of individual glasses, tumblers, or the like intended for the purpose of serving as many different individuals.

Among the objects of the invention is to provide a tray designed especially for use by a nurse in a hospital in her attendance upon a number of different patients to whom medicines or the like of different characters are to be administered in a safe, rapid, and sanitary manner. I wish it to be distinctly understood, however, that the invention in all of its main aspects is adapted for a wider field of usefulness than that above indicated.

Figure 1 is a plan view of a tray embodying my improvements adapted for the support of twelve tumblers, parts being broken away.

Fig. 2 is a vertical transverse section on the line 2—2 of Fig. 1, but indicating one of the tumbler covers lifted.

Fig. 3 is an enlarged plan view of a portion of the device showing especially the nature of the hinge and the spring clip for holding the card; and

Figs. 4 and 5 are suggestions of the manner of inscribing the front and rear faces of a tumbler cover card.

Referring now more particularly to the drawings, I show a tray comprising a base 10 which may be essentially rectangular and provided with a rolled edge 11 for reinforcement, and to provide a slight elevation of the base above the table. The base as well as the parts attached thereto is preferably made of metal or some similar material of a durable nature and preferably enameled so as to withstand any reasonable degree of heat for sterilizing purposes.

Secured to and extending upward from the longitudinal median line of the base are uprights or standards 12 having right angularly turned feet 13 fixed as by rivets 14 upon the upper surface of the base. The upper ends of the standards 12 are con-

nected by a horizontal bar 15 which in addition to stiffening and bracing said standards may serve either as a handle or attachment means for any suitable handle for the manipulation of the tray as a whole. This bar is shown as a channel member, the leg portions of the channel spanning the upper ends of the standards and secured thereto by rivets 16.

Each standard 12 is shown provided with a pair of oppositely arranged holding arms 17 terminating in loops or rings 18 in the same horizontal plane, the inner or adjacent ends of the arms being bent downward at right angles as shown at 19 and secured to the standard by rivets 20 common to both of the arms. The loops 18 are calculated to receive and reliably support from lateral displacement as many glasses or tumblers supplied with medicines for the several patients. Each arm and its loop are spaced sufficiently from the next adjacent arm and loop to enable the nurse to manipulate any tumbler without touching or disturbing any other tumbler. The loops may constitute the sole support for the tumblers, but preferably they are large enough to permit the tumblers to stand on the base 10.

Above the arms 17 are a like number of brackets 21 secured to the standard 12 by rivets 22 in a manner similar to the means for securing the arms. To the outer horizontally disposed portions of the brackets are freely pivoted a plurality of clips 23, each comprising a flat member or plate 24 having a rectangular outer end and a narrower rectangular inner end and provided close to its center with a pair of laterally projecting pintles 25 pivoted in downwardly curved bearings 26 formed in a pair of fingers 27 at the outer end of the bracket. The space between the fingers permits free pivotal or swinging movement of the clip, limited only, however, in the outward and downward swinging by the narrow inner end of the plate striking directly against the under surface of the bracket. This plate member may readily be formed from flat sheet metal by a simple stamping or punching process. To the upper face of the clip is fixed a leaf spring 28 the outer free end of which is adapted to bear upon the upper surface of the broader end of the plate 24 and so resiliently grip the inner or lower edge of a memorandum card 29 which is adapted to lie flat upon a tumbler supported

in the arm below the bracket under consideration. Obviously the cards may easily be removed or interchanged from the clips when necessary.

5 Each card 29 constitutes immediately a cover for a tumbler when supported as indicated, whereby the contents of such tumbler are kept as free as possible from contamination. Moreover each card preferably constitutes an indicator as may be observed from the two faces thereof represented in Figs. 4 and 5 at 29^a and 29^b respectively showing any suitable identification means for the several patients or directions, orders, observations, or the like pertinent to the nurses' duties, all as will be well understood and appreciated by those skilled in the art. The card may be individually inscribed either before or after its introduction into the clip. Of the utmost importance, however, is the fact that for the use by a nurse who is charged with the attendance upon a number of different patients requiring different prescriptions, there can be no reasonable possibility for her to make an error in the administering of the medicines, and furthermore there is no immediate likelihood that she may spill any of the medicines or break the tumblers unless grossly careless, which is not to be presumed. In my experience, however, in the hospital I am aware that by reason of the clumsy facilities that obtain in many even well regulated hospitals, a nurse upon whom devolves the duty of attending a great many patients often times confuses the medicines and directions pertaining individually there-

to; also I have seen a busy nurse in her attempt to serve a number of patients frequently spill medicines and break the apparatus without suitable facilities for manipulating the tumblers. The convenience and reliability of this contrivance are materially increased by providing individual identification marks on the brackets 21 and on the respective cards 29 coöoperating therewith.

I claim:

1. In a medicine tray, the combination of a base adapted to directly support a plurality of tumblers, rigid means extending upward from the longitudinal center of the tray, individual tumbler holding means connected to said upright means and extending laterally therefrom, a plurality of brackets fixed to the upright means above the holding means, a series of individual and distinguishing covers for the several tumblers, and a plurality of cover holding clips pivotally connected for movement around the horizontal axes on said brackets.

2. In a medicine glass holder, the combination of a base, a rigid upright standard fixed to the base, a horizontal arm fixed to the standard having means to embrace the glass holding it upon the base, an identification cover for the glass, and a spring clip to hold the cover and permanently pivoted to the upright above the top of the glass, said clip being adapted to support the cover in flat position upon the glass and to allow the same to swing upward and tilt rearward against the upper end of the standard.

WILBUR B. GRANT.
